UNITED STATES PATENT OFFICE

2,556,538

SLIDING DIE TYPE DRIP MOLDING
RESHAPING TOOL

Frederick J. Hauschild, Oneonta, N. Y.

Application March 11, 1946, Serial No. 653,453

4 Claims. (Cl. 81—15)

1

This invention relates generally to the class of tools and pertains particularly to improvements in tools for use by automobile body repairers for straightening or restoring the body part to its original condition.

A principal object of the present invention is to provide a novel tool designed for use in straightening dented or mashed drip moldings of automobile bodies, the tool being particularly designed to be used in association with a force applying tool and more especially a pneumatic hammer head of the type illustrated in my issued Patents Nos. 2,148,619 and 2,148,943, both issued February 28, 1939.

Another object of the invention is to provide a repair or straightening tool for restoring bent or mashed drip moldings to their former condition, which is constructed to be easily and quickly applied to the moldings and which is provided with an anvil or driving element to which a driving force may be readily applied whereby to effect the movement of the straightening tool along the molding.

Another object of the invention is to provide a drip molding straightening tool of the character stated which is designed with coacting parts for engaging the inner and outer surfaces of the molding and which parts are so constructed that, as a driving force is applied to the tool to move it in one direction lengthwise of the molding, the molding will be forcibly reshaped and restored to its former contour.

Other objects and advantages of the present invention will become apparent as the description of the same proceeds and the invention will be best understood from a consideration of the following detailed description taken in connection with the accompanying drawings forming a part of the specification, with the understanding, however, that the invention is not confined to a strict conformity with the showing of the drawings but may be changed or modified so long as such changes or modifications mark no material departure from the salient features of the invention as expressed in the appended claims.

In the drawings:

Figure 1 is a view in perspective of one embodiment of the present invention, constructed in the form of a plier and illustrating, in broken lines, the manner in which a pneumatic hammer may be employed for working the tool along a molding.

Figure 2 is a view in elevation of the face of the tool, looking at the engaged jaws.

Figure 3 is a view of the side of the tool head opposite from the driving rod or anvil.

Figure 4 is a detail section illustrating one method of coupling the handles of the tool together.

Figure 5 is a view partly in elevation and partly

2

in section of another embodiment of the drip molding straightener.

Figure 6 is a view in perspective of the second embodiment.

Referring now more particularly to the embodiment of the invention illustrated in Figures 1 to 4 inclusive it will be seen that the tool comprises two coacting jaw members 10 and 11. One of the jaw members, here designated 10, has formed integral therewith the relatively long substantially straight handle or arm 12 which is provided at its free end with the slot 13. The head 10 has a rectangular opening or slot 14 therethrough which is in a plane perpendicular to the width of the head.

The jaw head 11 has the upwardly curving shank portion 15 which passes through the slot 14 and which merges with the relatively long straight handle 16 which, when the jaws are closed, extends substantially parallel to the handle 12. This handle 16 also has, in its free end, the slot or opening 17.

A pivot pin 18 passes through the head 10 and through the shank portion 15 of the head 11 so that these two heads work together as cooperating jaws.

As shown in Figure 3 the forward face of the lower jaw 11 is undercut or cut back as indicated at 19 and extending across the forward face of the jaw 11 at the top of the undercut wall 19 is the channel or gutter 20 which, at one end, is rounded as indicated at 21. This rounded end edge of the gutter 20 is at the end of the gutter which opens through the side of the tool 35 which is the advancing side when the tool is in use. It will also be noted that the gutter opens upwardly in a direction extending substantially in a plane parallel with the undercut forward face 19 and the outer side of the gutter merges 40 with the upper part of the wall 19 forming the relatively sharp lip 22.

The top jaw or head 10 has formed integral with the underside thereof at the forward lower corner, the depending shaping or molding rib 23, the under half of which is substantially semicircular in cross section or otherwise formed to conform to the original shape of the inner side of the drip molding upon which the tool is to be used. The end of this shaping rib 23 which advances in the use of the tool, is rounded as indicated at 24 for coaction with the rounded edge 21 of the gutter. Thus when the tool is in position and is forcibly advanced along the drip molding the deformities of the molding will be forced smoothly between these rounded edges and between the coacting rib and the gutter surfaces so as to smooth and straighten the molding to restore it to its original form.

At the rear or trailing side of the tool head 50 one of the jaw members, here shown as the upper

jaw 10, is provided with a suitable threaded bore 25 to receive the threaded end of a driving rod or anvil 26.

While any suitable means may be used for applying force to the end of the anvil rod 26, the present invention has been designed with a view to using a pneumatic driving unit of the character illustrated in my patent hereinbefore referred to. The nose end of the cylinder and the hammer head of this pneumatic driving unit are here conventionally shown and designated 27 and such unit head includes a suitable receiver into which the end of the anvil rod 26 may be inserted to receive impact blows from a reciprocating hammer forming a part of the head.

Figure 1 shows the tool applied to a drip molding which is generally designated 28. As will be readily understood, in applying the tool the handles 12 and 16 are swung apart so as to separate the coacting members or parts of the two jaws, whereupon the molding is positioned in the jaw gutter 20 and when the tool is closed the shaper rib 23 will enter the molding so that the latter will be held in the tool.

In order to hold the jaws together with the proper degree of tension, one of the handles herein shown as the handle 12, is provided with the transverse pivot pin 29 which passes through the eye 30 of a screw 31. The eye 30 is positioned in the recess or slot 13 and the screw is oscillated on the pin 29 to bring the other end into the slot 17 whereupon a wing nut 32 is applied to the screw and is threaded down upon the upper side of the handle 15, thereby drawing the handles together.

The proper degree of tension is applied to the handles so as to snugly secure the molding 28 between the cooperating portions of the jaws whereupon the application of driving force to the end of the anvil rod 26 will force the tool along the molding and restore the latter to its original shape.

In the second embodiment illustrated in Figures 5 and 6 the coacting upper and lower jaws are illustrated as being in the form of blocks 33 and 34. These jaw blocks are supported in a frame body 35 which is generally C-shaped and comprises the relatively long back part 36 and the spaced parallel ends 37 and 38. The lower jaw 34 is provided with the transverse recess or channel 39 which receives the lower part 37 of the holder or frame 35 and the back of both the lower jaw 34 and the upper jaw 33 has a channel or recess 40 in which is slidably received the back part 36 of the frame.

The lower jaw block 34 is maintained in position preferably by a screw 41 while the upper jaw has a socket 42 in the top thereof to receive the lower end portion 43 of a screw 44 which is threaded through an opening 45 in the upper part 38 of the frame 35. The upper or outer end of the screw 44 is formed integral with or has secured thereto the handle 46.

As shown in Figure 5 the inner end portion 43 of the screw 44 is provided with the circumferential channel 47 which receives the inner end of a set screw 48 which is threaded into the block 33 from the front side, so as to swivel couple the screw with the block.

The lower jaw block 34 is provided with the molding receiving gutter or lower die 49 in which the molding, here shown in broken lines and designated 50, is positioned.

Coacting with the lower die or gutter 49 is the upper die or depending shaper rib 51 which

forms a part of the upper jaw block 33 and extends downwardly to position in the lower die or gutter 49 as illustrated.

At the advancing ends of the jaw blocks 33 and 34, the edges of the upper and lower dies 51 and 49 are rounded as indicated at 52, in the same manner as the corresponding members of the first described embodiment while at the rear or trailing ends of the jaw blocks, the upper block 10 has secured therein the anvil rod 53 against the end of which driving blows are applied by a suitable implement, preferably by means of an air tool or air hammer of the character hereinbefore referred to. In Figure 6 the nose end and hammer head of the air tool or air hammer are shown conventionally in dotted outline and is designated 54 with the head in operative connection with the anvil 53.

It will be readily seen from the foregoing that there is provided in the present invention a tool which can be easily and quickly applied to a drip molding and which is easily operated, particularly when using an air hammer of the character stated, to restore a bent, dented or mashed molding to its original form.

I claim:

1. A drip molding reshaper and straightener comprising a pair of jaw members, means coupling the jaw members together for relative movement, means for effecting relative movement between the jaw members, coacting dies carried by the jaw members, one of the dies comprising a relatively long gutter in which the underside of a molding may be positioned and the other die constituting a relatively long forming rib designed to enter the gutter and to enter a molding positioned in the gutter, and an anvil rod connected with one of the jaws and extending in substantially the same direction as the coacting dies and adapted to receive driving blows against its outer end to move the dies longitudinally of an engaged drip molding.

2. An implement of the character stated in claim 1 in which the adjacent edges of the coacting dies at the advancing ends thereof are rounded to facilitate the movement of the dies longitudinally of an engaged molding.

3. A drip molding reshaper and straightener comprising a pair of jaw members, means pivotally coupling the jaw members together for relative movement of adjacent portions thereof, handles connected to the jaw members to facilitate relative movement of the same, a pair of die members carried by the jaws, one of said die members constituting a relatively long gutter formed in one jaw for the reception of the lower part of a drip molding, the other die constituting a relatively long rib carried by the other jaw and adapted to enter said gutter and to enter a molding positioned in the gutter, and an anvil member carried by a jaw for facilitating the application of driving blows to the jaws at one end of the coacting dies, the said means for applying driving blows to the jaws comprising a relatively long anvil rod secured to one of the jaws and extending longitudinally of the dies.

4. A drip molding reshaper and straightener of the character described, comprising a pair of jaw members, coacting dies carried by the jaw members, one of said dies being in the form of a relatively long gutter designed to receive the underside of a molding, the other die being in the form of a relatively long rib adapted to position in the gutter, a frame supporting said dies and including a relatively long back portion

and a right angularly extending end portion, one of said jaws being secured to the back portion, the other jaw being slidably positioned against the back portion between the fixed jaw and the said right angularly extending portion, a screw threaded through said right angularly extending portion and having an end swivelly coupled with the said other jaw, means for rotating the screw, said screw when rotated functioning to move the said other jaw relative to the fixed jaw to bring the dies into or out of working relation, and means carried by an end of one of the jaws for facilitating the application of driving blows to the said one of the jaws to cause the jaws to move longitudinally of a molding engaged between the dies, the last named means comprising a relatively long anvil rod secured to the said one of the jaws to extend therefrom longitudinally with respect to the dies.

FREDERICK J. HAUSCHILD.
